UNITED STATES PATENT OFFICE

165,945

SEMIMOUNTED CORN HARVESTER

Erich J. Stumpenhorst, Chicago, Ill., assignor to
Farm-Rite Implement Company, a corporation
of Illinois

Application October 14, 1950, Serial No. 12,580

Term of patent 14 years

(Cl. D40—1)

To all whom it may concern:

Be it known that I, Erich J. Stumpenhorst, a citizen of the United States, residing at Chicago, in the county of Cook and State of Illinois, have invented a new, original, and ornamental Design for a Semimounted Corn Harvester, of which the following is a specification, reference being had to the accompanying drawing, forming a part thereof.

In the drawings, Figure 1 is a perspective view of the front and the outside of a semimounted corn harvester, showing my new design; and Fig. 2 is a perspective view of the front and the inside thereof.

I claim:

The ornamental design for a semimounted corn harvester, as shown.

ERICH J. STUMPENHORST.
